UNITED STATES PATENT OFFICE.

JOHN TAYLOR, JR., OF KANSAS CITY, MISSOURI.

HUMIDOR.

1,144,508.

Specification of Letters Patent. Patented June 29, 1915.

Application filed July 13, 1914. Serial No. 850,542.

To all whom it may concern:

Be it known that I, JOHN TAYLOR, Jr., a citizen of the United States, residing in Kansas City, in the county of Jackson and State of Missouri, have invented certain new and useful Improvements in Humidors, of which the following is a specification.

My invention relates to improvements in humidors particularly adapted for moistening cigars.

One of the objects of my invention is to provide a humidor which will discharge moisture near the bottom of the case in which it may be placed. As the moist air is usually warmer than the air in the case, it will rise after its discharge from the humidor, thereby effecting an even distribution of the moisture.

Another object of my invention is to provide a humidor from which either moist or dry air may be discharged into the case containing the cigars.

Still another object of my invention is to provide novel means for regulating the amount of moisture or dry air which is discharged from the humidor.

Still another object of my invention is to provide a humidor which is ornamental in appearance, is easily operated and which may be employed for advertising purposes.

Other novel features are hereinafter fully described and claimed.

In the accompanying drawings, which illustrate the preferred embodiment of my invention, Figure 1 is a central vertical sectional view of my improved humidor. Fig. 2 is a horizontal sectional view on the line 2-2 of Fig. 1, the lamp being removed. Fig. 3 is a bottom view of the humidor.

Similar reference characters indicate similar parts in the different views.

1 designates a base plate, which may be of any desired form, and which, in the drawing, is shown rectangular.

2 designates a water receptacle, preferably of transparent material, such as glass, and which is provided with an upwardly and inwardly extending hollow dome 3 into which is fitted, preferably loosely, the upper end of a tubular projection 4 with which the upper side of the base 1 is provided.

The periphery of the tubular projection 4

is provided with an annular shoulder 5 upon which the receptacle 2 is adapted to rest.

The upper side of the base 1 is provided with two lugs 6 to which are respectively secured the lower ends of two upstanding spring catches 7 having on their inner sides rounded projections 8 respectively adapted to enter two recesses 9, which are provided in the outer sides of opposite walls of said receptacle. The spring catches 7 releasably fasten the receptacle 2 to the base 1.

The upper end of the receptacle 2 is open and discharges into an outer casing 10 which incloses the receptacle 2 and is spaced apart therefrom at the sides and top, thereby forming a passage 11 through which moisture may pass from the receptacle 2.

The lower end of the casing 10 is open, but is normally closed by the base 1 upon which the casing rests and to which it is releasably fastened by two spring catches 12, similar to the catches 7 and respectively secured to the inner sides of two upstanding flanges 13 with which the base 1 near its side edges is provided. The casing 10 at opposite outer sides is provided respectively with two recesses 14 adapted to respectively receive two rounded projections provided respectively on the inner sides of the catches 12 and designated by 15.

To prevent the receptacle 2 turning on the base 1, said receptacle is provided on the inner side of the dome 3 with a projection 16 adapted to enter a notch 17 in the upper edge of the tubular projection 4.

The dome 3 with the tubular projection and base 1 forms a heating chamber in which is located a heating device, preferably an electric lamp 18, the wires 19 of which extend through a central hole 20 in the base 1 and are connected to a suitable current source, not shown.

The base 1 is provided inside the tubular projection 4 with a plurality of vertical holes 21 through which heated air from the heating chamber may pass. The base 1 is also provided with a plurality of vertical holes 22, located outside the projection 4 and communicating with the passage 11 by means of a space provided between the receptacle 2 and the base 1.

A horizontal disk valve 23 is centrally

pivoted to the under side of the base 1, and is provided with a laterally projecting handle 24, which extends through a notch 25 provided in a downwardly extending flange 26 on the under side of the base 1. The side walls of the notch 25 limit the movement in both directions of the handle 24 and valve 23. Said valve 23 is provided with two circular rows of vertical holes 27 and 28 adapted respectively to register with the holes 21 and 22. The disposition of said holes 27 and 28 is such that when one set of holes are in register with one set of holes in the base 1, the other set of holes will be out of register with the other set of holes in the base. By properly positioning the valve 23, the hole 21 may be wholly closed while the holes 22 are wholly open. When so arranged, moisture caused by the heating of water in the receptacle 2, will pass out the open top of the receptacle, thence downwardly through the passage 11, and thence under the receptacle 2 and through the holes 22 and 28. From under the base 1, the moisture will pass by way of the notch 25 and similar notches 29, provided in the lower edges of other downwardly extending marginal flanges 30, with which the base is provided. If dry air is desired to be discharged into the case, the valve 23 is turned to a position in which the holes 27 will register with the holes 21. Dry air will then pass from the heating chamber to the lower side of the base 1, and from thence being discharged into the case by way of the notches 25 and 29. At such time the valve 23 will close the openings 22, so that no moisture will pass from the humidior into the case containing it. If moisture is to be discharged into the case, the valve 23 is turned so that the holes 28 will register with the holes 22. At this time the valve 23 will close the holes 21 and no air from the heating chamber can pass from the humidior. The lamp 18 will heat the water in the receptacle, thus driving off moisture which will pass from the receptacle 2, by way of the passage 11 to the openings 22 and 28, thence passing through these openings and escaping by way of the notches 25 and 29 into the case. As the moisture is discharged from the bottom of the humidior, instead of from the top thereof, there will be a more even distribution of the moisture in the case than could otherwise be effected. In case that it is desired to discharge moist air mixed with dry air, the valve 23 is turned so that the openings 27 and 28 respectively communicate with the openings 21 and 22. By proper regulation of the valve, the desired mixture may be obtained.

It will be obvious that my improved humidior may be used for various other purposes than the moistening of cigars.

If desired, the side walls of the receptacle

2 and of the casing 10, and the top of the casing 10, may have advertising matter or other display matter inscribed thereon, which will be illuminated by the lamp 18.

I do not limit my invention to the structure shown and described, as modifications, within the scope of the appended claims, may be made without departing from the spirit of my invention.

Having thus described my invention, what I claim and desire to secure by Letters Patent, is:—

1. In a humidior, a base having an opening communicating with the atmosphere, an outer casing having an open lower end communicating with said opening and closed by said base, a water receptacle inclosed by said outer casing and having an opening for discharging moisture into said casing, and provided with an inwardly extending hollow dome forming with said base a heating chamber, and a heating device in said chamber. 80

2. In a humidior, a base having an opening communicating with the atmosphere, an outer casing having an open lower end closed by said base, a water receptacle inclosed by and spaced apart at the sides and top from said outer casing, said receptacle having an open top and being provided with an inwardly extending hollow dome forming with said base a heating chamber, the space between the casing and receptacle communicating with said opening in the base, and a heating device in said chamber. 90

3. In a humidior, a base having an opening communicating with the atmosphere, a valve controlling said opening, an outer casing having an open lower end closed by said base and communicating with said opening, a water receptacle inclosed by and having an opening for discharging moisture into said outer casing, and provided with an inwardly extending hollow dome forming with said base a heating chamber, and a heating device in said chamber. 105

4. In a humidior, a base having an opening communicating with the atmosphere, an outer casing having an open lower end closed by said base and communicating with said opening, a water receptacle inclosed by and having an opening for discharging moisture into said outer casing, and provided with an inwardly extending hollow dome forming with said base a heating chamber, said base having an opening communicating with the atmosphere and with said heating chamber, and a heating device in said chamber. 110

5. In a humidior, a base having an opening communicating with the atmosphere, an outer casing having an open lower end closed by said base and communicating with said opening, a water receptacle inclosed by and having an opening for discharging moisture into said outer casing, and pro- 125

65

130

vided with an inwardly extending hollow dome forming with said base a heating chamber, the base having an opening communicating with the atmosphere and with 5 said heating chamber, a valve controlling the last named opening, and a heating device in said chamber.

6. In a humidor, a base having an opening communicating with the atmosphere, an 10 outer casing having an open lower end closed by said base, a water receptacle inclosed by and spaced apart at the sides and top from said outer casing, said receptacle having an open top and provided with an inwardly 15 extending hollow dome forming with said base a heating chamber, the space between the casing and receptacle communicating with said opening in the base, the base having an opening communicating with the atmosphere and with said chamber, and a heating 20 device in said chamber.

7. In a humidor, a base having two openings communicating with the atmosphere, an outer casing having an open lower end 25 closed by said base and communicating with one of said openings, a valve adapted to close one of said openings, a water receptacle inclosed by and having an opening for discharging moisture into said outer casing, 30 and provided with an inwardly extending hollow dome forming with said base a heating chamber, one of the openings in the base communicating with said heating chamber, and a heating device in said chamber.

35 8. In a humidor, a base having two openings communicating with the atmosphere, a valve for controlling said openings and arranged to be closed with respect to one opening, while it is open with respect to the other 40 opening, an outer casing having an open lower end closed by said base and communicating with one of said openings, a water receptacle inclosed by and having an opening discharging into said outer casing, and 45 provided with an inwardly extending hollow dome forming with said base a heating chamber, the other opening in the base communicating with said chamber, and a heating device in said chamber.

50 9. In a humidor, a base having on its upper side a tubular projection and provided at the inner side and outer side of said projection with two openings respectively, said openings communicating with 55 the atmosphere, a receptacle for water having an open top and provided with an inwardly extending hollow dome forming with said tubular projection a heating chamber, a heating device in said chamber, 60 and an outer casing inclosing said receptacle and spaced apart at the sides and top therefrom and having an open lower end closed by said base and communicating with the opening in the base which is outside said tubular projection.

10. In a humidor, a base having on its upper side a tubular projection and provided with two openings respectively at the inner and outer sides of said projection and communicating with the atmosphere, a valve 70 controlling said openings and adapted to be open with respect to one opening while it is closed with respect to the other opening, a receptacle for water having an open top and provided with an inwardly extending 75 hollow dome forming with said projection a heating chamber, a heating device in said chamber, and an outer casing inclosing and spaced apart at the sides and top from said receptacle and having an open lower end 80 closed by said base and communicating with the opening which is at the outer side of said tubular projection.

11. In a humidor, a base having on its upper side a tubular projection and having 85 two openings respectively at the inner and outer sides of said projection and communicating with the atmosphere, a valve controlling said openings and arranged to be closed with respect to one opening while it 90 is open with respect to the other opening, a receptacle for water having an open top and provided with an inwardly extending hollow dome into which the upper end of said projection fits, means for releasably 95 locking the receptacle to said base, said dome forming with said projection a heating chamber, a heating device in said chamber, an outer casing inclosing said receptacle and spaced apart therefrom at the 100 sides and top, and having an open lower end closed by said base and communicating with the opening in the base which is at the outer side of said projection, and releasable means for locking the outer casing to the base. 105

12. In a humidor, a water receptacle having an inwardly extending hollow dome, an outer casing inclosing said receptacle and into which the receptacle is adapted to discharge moisture, said receptacle and casing forming a passage for moisture leading downwardly in the casing, a base supporting said receptacle and casing and forming with said dome a heating chamber, the base having two openings communicating with 115 the atmosphere and communicating respectively with said passage and with said chamber, and a heating device in said chamber.

13. In a humidor, a water receptacle having an inwardly extending hollow dome, an outer casing inclosing said receptacle and into which the receptacle is adapted to discharge moisture, the receptacle and casing forming a passage for moisture leading downwardly in the casing, a base supporting the receptacle and casing and forming with said dome a heating chamber, the base having two openings communicating respectively with said passage and with said chamber and communicating with the at- 120 125 130

mosphere, a heating device in said chamber, and a valve controlling said openings and arranged to be open with respect to one opening while it is closed with respect to 5 the other opening.

14. In a humidor, a water receptacle having an inwardly extending hollow dome, an outer casing inclosing said receptacle and into which the receptacle is adapted to discharge moisture, the receptacle and casing forming a passage for moisture leading downwardly in the casing; a base supporting said receptacle and casing and forming with the dome a heating chamber, the base 15 having a downwardly extending supporting flange provided with a notch in its lower edge, the base having two openings vertically therethrough communicating with the

passage and chamber respectively, a heating device in said chamber, and a valve pivoted 20 to the under side of said base and having a handle extending through said notch, the side walls of said notch being adapted to limit the swing of said valve, the valve being arranged to control said openings and 25 being adapted to be closed with respect to one of the openings while it is open with respect to the other opening.

In testimony whereof I have signed my name to this specification in the presence of 30 two subscribing witnesses.
